DESIGN FOR A COMBINED BASE AND PED- ESTAL FOR TABLE LAMPS

Jane Wilcox, Chicago, Ill., assignor to Electrical
Testing Laboratories, New York, N. Y., a cor-
poration of New York

Application August 27, 1938, Serial No. 79,599

Term of patent 3½ years

To all whom it may concern:

Be it known that I, Jane Wilcox, a citizen of the United States of America and a resident of Chicago, in the county of Cook and State of Illinois, have invented a new, original, and ornamental Design for a Combined Base and Pedestal for Table Lamps, of which the following is a specification, reference being had to the accompanying drawing, forming a part thereof.

Figure 1 is a side elevation of a combined base and pedestal for table lamps, showing my new design.

Figure 2 is a fragmentary top plan view taken in the direction of arrow 2 of Fig. 1, and

Figure 3 is a fragmentary plan view of the base taken in the direction of arrow 3 of Fig. 1.

The side opposite to the side shown is substantially the same in appearance as the side shown.

I claim:

The ornamental design for a combined base and pedestal for table lamps, as shown and described.

JANE WILCOX.
